UNITED STATES PATENT OFFICE.

IVER JOHNSON, OF ABBOTSFORD, WISCONSIN.

DEVICE FOR OPENING CANS.

1,057,842.

Specification of Letters Patent.

Patented Apr. 1, 1913.

Application filed February 8, 1912. Serial No. 676,195.

To all whom it may concern:

Be it known that I, IVER JOHNSON, a citizen of the United States, residing at Abbotsford, in the county of Clark and State 5 of Wisconsin, have invented certain new and useful Improvements in Devices for Opening Cans, of which the following is a specification.

This invention relates to a device for 10 opening cans and the like.

The object of the invention is to produce a device of this character which may be conveniently connected to the cover of a can or pail of the slip or friction type, so that such 15 cover may be easily removed without the aid of a separate tool which would tend to injure the body of the can or pail so that the contents thereof would have to be removed.

20 It is a well known fact that when it is desired to open cans of this type, the covers must be pried therefrom, and it is a further object of this invention to provide as a part of the can the hereinafter described opening 25 device.

With these and other objects in view, the invention consists in certain novel features of construction, combination, and arrangement of parts as will be hereinafter fully 30 described and claimed.

In the drawing: Figure 1 is a top plan view of a can showing the device in place thereon. Fig. 2 is a sectional view on line 2-2 of Fig. 1. Fig. 3 is a similar view 35 showing the device after the same has been operated to dislodge the cover.

Referring to the drawing, the numeral 1 designates the can, the same being provided with a central opening 2, and into which the 40 cover 3 fits, said cover and can being of that type commonly known as slip or friction.

The slip cover 3 is identical to those in common use, with the exception that the same is provided near the outwardly turned 45 flange 4 with a horizontally disposed slot 5, and through which the outer end of the lever 6, forming the opening device, projects. The lever 6 is formed from a strip of stout

sheet metal and is provided at its inner end with a disk 7 so that the same may be 50 readily grasped for operation.

To prevent accidental removal of the lever 6, a strip 8 is employed, the inner end of which is riveted to the lever, while its outer end is bent upwardly, and thence downwardly, as at 9, the downwardly bent end resting against the outer projected end of the lever 6. Thus it will be seen that the lever 6 is pivotally connected to the cover 3, and when the cover is in its proper position to close the can, the outer end of the lever rests upon that portion of the can which encircles the opening 2, thus forming a fulcrum for the lever.

From this construction it will be seen that 65 the inner end of the lever, or that part which carries the disk 7 is located centrally of the cover 3, and in a convenient position for grasping when it is desired to remove the cover, and to do this it is only necessary 70 that the disk 7 be grasped and the lever swung upon its pivot until the cover has been pried from the opening 2 sufficiently to permit further removal of said cover. It is obvious from this construction that after 75 the cover has been once removed, the same may be replaced to effectually close the can and preserve the contents thereof.

From the foregoing description it will be seen that a device for removing can covers 80 has been provided, which is simple in construction, and efficient in operation, and one which will in no way interfere with packing of the goods for shipping.

To limit the outward movement of the 85 lever 6 a shoulder 10 is formed thereon, which bears against the inner surface of the outwardly turned flange 4.

What is claimed is:

In combination with a can having a filling opening, an inclined top portion surrounding the filling opening, a cover for the can having a slot formed in its annulus, of a lever having its outer end projecting through said slot, a shoulder formed upon 95 the lever to limit the outward movement of

the same, a strip secured to the lever and having its portion so bent as to surround the edge of the can, the outer end of said strip engaging the projected end of the lever, thereby pivotally connecting the lever to the cover, said lever having its projected end adapted to rest upon the inclined top portion, a disk secured to the inner end of the lever, whereby when said disk is grasped

the lever may be swung upwardly thus dis- 10 lodging the cover from the can.

In testimony whereof I affix my signature, in presence of two witnesses.

IVER JOHNSON.

Witnesses:

MAY G. JOHNSON,
HARRY FARLEY.
